ROOFING.

Application filed July 16, 1925. Serial No. 44,132.

This invention relates to roofing material of the type commonly referred to as prepared roofing, and has to do more particularly with a novel roofing material which affords numerous advantages over the roofings heretofore made, by reason of the presence of metal suitably applied so as to cover portions of the normally exposed area of the roofing elements. The invention also includes a process 10 of making the new product.

So-called prepared roofings, as heretofore made and in common use, consist of a base of a non-metallic water-resistant material, which may be made of various materials. 15 The ordinary type of such roofing includes a base made of a sheet material of fibrous character, such as rag felt, which is saturated and coated with a water-proofing material such as a bituminous substance, of which asphalt 20 is an example. Ordinarily, a wear surface of granular material, such as crushed slate, is applied to the surface of the roofing material, and partially embedded therein. The slate forms a fire- and weather-proof surface which 25 protects the base and adds greatly to the life of the product. However, between the particles of the granular material, the coating substance is exposed, and occasionally, after extended periods of use, some of the granular 30 particles may be dislodged.

The object of this invention is to provide an improved roofing product of the type above referred to which offers numerous advantages over roofings as heretofore made, 35 by reason of the use of a layer of metal which is applied to the surface of the roofing in such a way that the metal occupies the interstices between the granular particles, thus serving to bond these particles together and 40 to the underlying coating. The metal entirely covers the interstitial coating layer, but the projecting granular particles are exposed. The metal is preferably applied as described, by electrodeposition, and copper is 45 particularly desirable, not only on account of the ease with which it may be deposited, but also because of its resistance to corrosion upon exposure to the weather, and its pleasing appearance. By a proper selection of the granular material to be used, highly ornamental color effects may be produced by the appli-

cation of the metal. At the same time the cost of the new roofing is not materially greater than that in which no metal is used, while the durability is comparable with a 55 metal surfaced-roofing because the only parts of the roofing which are exposed to the weather are either the granular particles, which are not affected by exposure, or the metal itself which has an indefinite life. The 60 presence of the metal also makes the new roofing product of increased rigidity without, however, stiffening it to the point where difficulties in laying it will be encountered.

For a better understanding of the invention, reference will be made to the accompanying drawings, in which,

Fig. 1 is a perspective view of a four-unit strip shingle of common form, with metal applied throughout the surface which is exposed to the weather when laid in the usual manner.

Fig. 2 is a similar view of a single shingle unit.

Fig. 3 is an enlarged sectional detail on the 75 line 3—3 of Fig. 2, with certain of the features shown diagrammatically.

Fig. 4 is a similar sectional view of a detail showing a slightly modified construction.

With reference more particularly to Fig. 3, 80 the base of the new roofing product is indicated at 1, and may consist of numerous materials. It is here indicated as being formed of a fibrous sheet, such as rag felt, sheeted on a paper machine and saturated with a water- 85 proofing material such as asphalt or other bituminous products, as indicated at 2. To the surface of this base is applied a coating 3, preferably of a high melting point asphalt, such as blown asphalt. Over this coating is applied a layer of granular material, such as crushed slate 5, which is partially embedded in the asphalt by applying the granular material thereto and rolling it into the coating while the latter is warm and soft. 90

In accordance with the principles of this invention, a layer of metal is now to be applied over the surface in which the granular material is embedded, the metal occupying the interstices between the granular particles 100 and serving to bond them together and to the base, and also to act as a protective covering

for such parts of the coating layer as are exposed between the granular particles. The metal coating is applied by electro-deposition, and since the asphalt and the granular material are non-conductive, it is necessary to provide a conductive layer throughout those surfaces where the metal is to be deposited.

There are a number of different methods which are effective for the application of the conducting coating on which the deposit is to be made. The most satisfactory method now known involves the application of the granular material to the base while the asphalt coating is hot, the granular material being distributed in such a way that the surface of the coating layer is not entirely covered. Immediately after the application of the granular material, a conductive layer of metallizing powder, such, for instance, as graphite, powdered metal, and other similar materials ordinarily employed for the purpose, is applied either by brushing the metallizing powder on the surface, so as to cover the coating layer exposed between the granular particles, or else by dusting on the metallizing powder. In the application of the metallizing powder by brushing or dusting, the entire surface including the granular particles, is covered by the powder, but those particles of the powder which cover the parts of the coating exposed between the granular particles are bound in place by the tacky coating surface. The surface on which the powder has been applied is now washed so that the powder which adheres to the top portions of the granular material is removed. The coated base is now placed in an electrolytic cell, and the metallizing powder forming the conductive coating is connected in the usual way so as to form the cathode in the cell.

The deposition is carried on until a layer of metal of the desired thickness is built up, when the element will have an appearance, as shown in Fig. 3, wherein the electro-conductive material is shown at 4, occupying the interstices between the non-conducting granular particles 5. The metal is deposited only over the conducting parts of the surface, as shown at 6, and the metal occupies the interstices between the granular particles and in many instances, partially overlies these particles so that the particles are bound firmly together and to the base. With the roofing element so formed, it will be seen that the only exposed parts of the element are covered either by metal or else formed of the granular material.

Another method for the production of this new material which has been found to be satisfactory, involves the use of the granular surfaced roofing of the ordinary type over which a thin coating of asphalt emulsion is applied. Such an asphaltic emulsion is disclosed in the patent to Kirschbraun, No. 1,302,810, and is known in the trade as

K-B, or road emulsion. Over the surface coated with this road emulsion, the metallizing powder is dusted and after the stock has dried sufficiently it is washed so as to remove the metallizing powder from the tops of the granular particles, the metallizing powder, however, still occupying the interstices between these particles. Thereafter, the deposition is carried on in the usual manner. A slight modification of the method above described involves the brushing of the granular surfaced roofing with a fairly thick road emulsion which is allowed to dry until it receives its initial set, after which it is washed so that the emulsion is removed from the tops of the granular particles. Thereafter, the metallizing powder is brushed or dusted on and when thoroughly dry, the material is washed so that the powder is removed from the tops of the granular particles, whereupon the stock is ready for the electrolytic treatment.

Another method for the production of the new product involves the application of the metallizing powder to the stock immediately after it has been coated with the hot asphalt, and after a layer of metallizing powder has thus been applied, the granular material is distributed over the surface and the particles are embedded, as by rolling. After such treatment, the base will be seen to have a layer of granular material and in the interstices between the granules the surface is coated with metallizing powder, upon which deposition may be made in the usual way. If desired, the granular particles and the metallizing powder may be mixed together dry and the resulting mixture embedded in the surface of the asphalt coating while the latter is still tacky. The same distribution of the conducting and non-conducting particles is thus brought about and deposition is carried on, as before.

Still another method involves the application of an asphalt emulsion, or some other analogous adhesive to the surface of the granular coated base. When the emulsion is dry, a suitable solvent is employed to clean the tops of the granular particles and to make the adhesive in the interstices tacky, after which the metallizing powder is dusted or brushed on. The surface is now washed so as to remove the powder from the tops of the granular particles, while leaving the conductive particles in the interstices. Also, the granular surface stock may be coated with graphited water, such as that known in the trade as Aquadag. The surface is allowed to dry, then the graphite is removed from the tops of the granular particles by a brushing operation. The conductive particles, however, as before, occupy the interstices between the granular particles.

Another method involves the production of the granular surface stock on a roofing ma-

chine with such a distribution of the granular substances that the asphalt coating is exposed between the granules. This product is then treated with a solvent so that the exposed portions of the asphalt layer are tacky, after which metallizing powder is applied in the usual manner.

Another method has been used involves the application of a fatty substance, as by rolling or otherwise, to the surface of a granular coated base. The fatty substance adheres to the tops of the granules. The surface so treated is then coated with an asphalt emulsion which enters the interstices between the granules which have not been covered by the fatty substances. The metallizing powder is then applied by brushing or dusting and when the emulsion is dry, this conductive substance is firmly bound to the base in the interstices between the projecting granules. The fatty substance is now washed from the tops of the granules, and the deposition is carried on in any convenient manner.

Another method which is similar to one of the preceding methods in certain respects, involves the application of the metallizing powder to the surface of a plain stock which has been coated with asphalt. A thin layer of the metallizing powder is applied while the asphalt coating is still warm and tacky, and the stock is then placed in an electrolytic cell and an extremely thin film of copper is deposited. Over the surface of the metal the granular material is now distributed, and the particles are embedded, as by rolling. During this operation the particles of the granular material penetrate the thin metallic film and the edges of the metal around the holes made by the granular material have a tendency to turn inwardly so as to bond firmly with the asphalt coating beneath the metal. The metal is now exposed between the granules, and may be used as a conducting layer on which a further deposit of metal is built up by electrodeposition to any desired thickness. The second layer of metal occupies only the interstices between the granules and acts to wedge these granules tightly in position.

A modified method of producing the product involves the use of granular material which is a mixture of conducting and non-conducting substances. The non-conducting granular material may be crushed slate or any of the other similar products used for the purpose, while the conducting granules may be made up of crushed petroleum coke, crushed carbon, and other similar substances. The mixture includes up to 75% of conducting material, and the particles are suitably graded as to size. The mixture of granular material is heated and then embedded in the surface of the stock coated with asphalt. If desired, the granular material may be applied while the asphalt coating is still hot and tacky, in

which event no heating of the granular material is required. When this process is used, as illustrated in Fig. 4, the finished product includes metal 12, which is deposited only over the conductive granules 10, while the non-conductive granules 11 are exposed through the metal layer at intervals over the surface.

By any of the methods above described, a product is produced having an exposed surface consisting either of metal or else of the portions of the granular material which are exposed through the metallic layer. Neither of these substances is detrimentally affected by exposure to the weather, and the life of the new product is, therefore, much longer than that of products heretofore used, in which no metal is used. Also, the desired durability is secured with a minimum expense for the metal because only those portions of the exposed surface of the roofing element which might be affected by the weather, are protected by the metal.

It is preferable in carrying out any of the methods above described, for the application of the metal in the interstices between the granules of the granular layer, to make provision for a coating of metal over the edges of the base. This can be accomplished in several ways, as, for example, in the application of the conductive coating this coating may be extended over the edges of the base which define the area which is to be exposed to the weather. In the deposition of the metal thereafter a layer of metal is plated over the conductive material at the edges of the base and is continuous with the metal coating which lies in the interstices between the granules on the face of the base. Also, if desired, another method for insuring that the edges are plated may be used involving the placing of the elements in stacks after the cut-outs have been formed. At this time the asphalt with which the bases are impregnated will ordinarily be sufficiently warm so that the metallizing powder when blown or dusted on the edges, will be bound in position. Thereafter, when the bases are placed in the electrolytic tank, the metal is deposited on the edges as before.

In the application of the metal, the entire surface of the base may be provided with a metallic layer which occupies the interstices between the granular particles, but it is preferable to confine the application of the metal only to such parts of the roofing product as will be exposed when the product is laid on the roof in the usual way. In the case of elements which are applied in overlapping courses in a manner similar to shingles but without spacing, only the forward edge of the base need be plated, as indicated by the shaded portion in Fig. 2. In the case of strip shingles in which cut-out indentations are formed in the forward edge, so as to define a plurality of tabs, a portion of each

shingle will be exposed through the cut-out indentations of the shingle in the course next above. It is, therefore, desirable to protect this exposed portion, and this is done by extending the plating rearwardly beyond the normally exposed margin of the shingle to form a plurality of tongues, as indicated in the heavy shading in Fig. 1. In order to limit the metal to the desired areas, it is only necessary to prevent its application beyond the boundaries of these areas, or this can be accomplished by restricting the electro-conductive material to the desired areas.

We claim:

13. Sheet material comprising a base having a facing of granular material, and metal lying in the interstices only of the facing.
14. Sheet material comprising a base having a facing of granular material, and a continuous layer of metal lying only in the interstices of the facing, beyond which the particles of the granular material project.
15. Sheet material comprising a non-metallic base having a facing of granular material and metal lying in the interstices only of said facing.
16. Sheet material comprising a non-metallic base having a facing of non-electro-conductive granular material, electro-conductive material in the interstices only of said facing, and metal covering the electro-conductive material only.
17. Sheet material comprising a fibrous base having a coating of asphaltic material, a surfacing of granular material partially embedded in this coating and metal lying in the interstices only of said surfacing.
18. Sheet material comprising a fibrous base having a coating of asphaltic material, a surfacing of granular material partially embedded in the coating, and electrodeposited metal only in the interstices of said surfacing.
19. Sheet material comprising a fibrous base having a coating of asphaltic material, a surfacing of non-electro-conductive granular material partially embedded in the coating, electro-conductive material in the interstices of said surfacing, and electro-deposited metal on said conductive material only.
20. Sheet material comprising a fibrous base saturated and coated with asphaltic material, a surfacing of non-electro-conductive granular material partially embedded in said coating, electro-conductive material in the interstices of said surfacing, and electro-deposited metal on the conductive material only.
21. Roofing having a surfacing of non-metallic granular material bonded by metal lying in the interstices only between the grains.
22. Sheet material surfaces with mingled electro-conductive and non-conductive materials, and electro-deposited metal over the conductive material only.
23. In combination, a base material, non-

electro-conductive granular material partially embedded in the surface thereof, electro-conductive material fixed to said base between the grains of non-conductive material, and electro-deposited metal on said conductive material only.

12. In combination, a base having a facing of non-conductive granular material fixed thereto, and deposited metal in the interstices only of said facing.

13. The method of surfacing material which comprises partially embedding granular material in the surface thereof, and electro-depositing metal in the interstices only between the grains.

14. The method of facing an asphaltic surface which comprises partially embedding non-electro-conductive material therein, fixing electro-conductive material in the interstices only between the grains, and electro-depositing metal on said conductive material only.

15. The method of facing a surface which comprises applying a coating of hot asphaltic material over the surface, partially embedding granular material in the coating, applying electro-conductive material to the coating between the granules only, and electrodepositing metal over the conductive layer only.

16. The method of facing a surface which comprises applying a coating of hot asphaltic material over the surface, partially embedding granular material in the coating, applying a film of electro-conductive material, washing the surface to remove the electro-conductive material from the tops of the granules only, and electro-depositing metal over the electro-conductive material only.

17. The method of facing a surface which comprises affixing granular material to the said surface, applying an adhesive to the granular surface, applying a film of electro-conductive material to the interstices only between the granules, and electro-depositing metal over the electro-conductive material.

18. The method of facing a surface which comprises affixing granular material to the said surface, applying an adhesive to the granular surface, applying a film of electro-conductive material over the adherent surface, removing the electro-conductive material from the tops of the granules only, and electro-depositing metal over the electro-conductive material only.

19. The method of facing an asphaltic surface which comprises fixing thereto electro-conductive and non-conductive material, the electro-conductive material being sufficient in amount to carry current over the surface, and electro-depositing metal over the conductive material only.

20. The method of facing a surface which comprises applying a coating of hot asphaltic material over the surface, applying a film of

non-metallic electro-conductive material over metallic layer where the latter is exposed the asphaltic material, electro-depositing a between the granules.

thin film of metal over the conducting coating, partially embedding granular material

- 5 in the surface in such manner that the granular material penetrates the thin metallic film, and then electrodepositing metal over the

In testimony whereof we affix our signatures.
